UNITED STATES PATENT OFFICE.

JEROME B. BELL, OF WILMINGTON, DELAWARE.

FONT OF MATRICES.

No. 865,073.

Specification of Letters Patent.

Patented Sept. 3, 1907.

Application filed September 13, 1906. Serial No. 334,533.

To all whom it may concern:

Be it known that I, JEROME B. BELL, a citizen of the United States, residing at Wilmington, Newcastle county, State of Delaware, have invented certain new and useful Improvements in Fonts of Matrices, of which the following is a specification.

In setting up tabular matter, on the linotype machine considerable difficulty has been experienced in spacing the matter in each line so that corresponding parts of the several lines will appear properly in vertical columns. This is due chiefly to the multiplicity of the runningwise widths of the bodies of the matrices, and the same objection applies whether the widths of the bodies are arranged on the so-called unit system or otherwise.

It is the object of my invention to reduce the number of different body widths in a font of matrices and to so proportion those used that the operator or compositor may readily estimate mentally the space occupied by a given number of characters and supply the necessary blanks or quads to fill out the desired column width or fraction of a column width.

To these ends my invention consists in dividing the alphabet, together with the numerals, spaces or quads, punctuation marks and other characters constituting a font of matrices, into three or four groups, preferably three, the bodies of each group bearing a definite relation to the bodies of each of the other groups.

The invention will be described with reference to the accompanying drawing, in which,—

Figure 1 is a face view of a number of linotype matrices having bodies of uniform size; Fig. 2 is a face view of other matrices of uniform size less in width than the bodies illustrated in Fig. 1; Fig. 3 is a similar view of matrices having bodies of less width than those shown in Fig. 2; Fig. 4 illustrates a line of matrices made according to my invention and assembled ready for casting. Fig. 5 illustrates the matrices of the letters M and W having bodies of uniform width and slightly wider than the bodies of the matrices shown in Fig. 1.

In illustrating my invention in Figs. 1 to 4, inclusive, I have divided the characters embraced in a font of matrices into three classes approximately according to the customary widths of their bodies. Most of the punctuation marks and the narrower letters, such as "i" and "t", are arranged upon bodies 10, as illustrated in Fig. 3, of uniform size. Most of the capital letters I arrange upon bodies 11, which are of an average width suitable for such letters, and which width is a multiple 50 of the body width of the bodies 10. The small letters, numerals, and certain other characters of intermediate size, I arrange upon bodies 12, which are preferably

twice as large as the bodies 10. Spaces or quads are also provided having body widths equal respectively to the bodies 10, 11 and 12. As illustrated in the drawing, the bodies 12 are twice the width of the bodies 10 and the bodies 11 are twice the width of the bodies 12 and four times the width of the bodies 10. These relations are practical and workable, although somewhat different proportions might be adopted within the scope and spirit of my invention.

In assembling a series of lines, such as that shown in Fig. 4, the operator or compositor having but three widths of bodies to deal with can readily estimate the amount of matter set up and can therefore estimate the amount remaining to be filled at any time, and he can thus quickly select the necessary spaces to fill in between columns or at the end of a line. Thus in the line illustrated, following the word "Pacific", he can assemble such number of any size of the blank spaces or quads as will approximately fill the desired space between the word "Pacific" and the following numerals "208", and can then, at a glance, determine the remaining space to be filled which must always be equal to one of the smallest matrix quads or a multiple thereof.

As the widths of the capital letters, "M" and "W" are somewhat greater than the other capitals it may be advisable in some instances to provide special bodies for them, as shown, for instance, in Fig. 5. In such case I prefer to use bodies which are five times the width of the smallest bodies, or five units in width, assuming the smallest bodies to be one unit in width. It will be understood that this may be done without departing from the invention. With some styles of type, I may make the bodies of the "M" and "W" four times the smallest width used, and the bodies of the other capital letters three times the smallest width used, with the exception of "I" and "J" which may have bodies the same as the small letters "a" and "b," etc. I prefer, however, to limit the number of body widths to three, as shown in the drawing.

Having thus described my invention, what I claim and desire to secure by Letters Patent is,—

As an improvement in matrices for linotype machines, a font of matrices comprising not exceeding four groups, the matrices of each of said groups being of uniform body width throughout, the body widths of the respective groups being different from each other and being multiples of the body width of the group having the smallest bodies, for the purpose set forth.

In testimony whereof I affix my signature in presence of two witnesses.

JEROME B. BELL.
